David Walker, INVENTOR
BY *Drake* *Co.*
ATTORNEY

UNITED STATES PATENT OFFICE.

DAVID WALKER, OF NEWARK, NEW JERSEY.

DESIGN FOR A STAIR-CARPET BUTTON.

SPECIFICATION forming part of Design No. 26,710, dated March 2, 1897.

Application filed January 23, 1897. Serial No. 620,476. Term of patent 7 years.

To all whom it may concern:

Be it known that I, DAVID WALKER, a citizen of the United States, residing at Newark, in the county of Essex and State of New Jersey, have invented and produced a new and original Design for Stair-Carpet Buttons; and I do hereby declare the following to be a full, clear, and exact description of the invention, such as will enable others skilled in the art to 10 which it appertains to make and use the same, reference being had to the accompanying drawings, and to letters of reference marked thereon, which form a part of this specification.

15 In said drawings, Figure 1 is a front elevation of my newly-designed stair-carpet button, and Fig. 2 is a section of the same on line *x*.

20 The leading feature of my new design consists of a stair-carpet button having on the face thereof star-shape ornamentations disposed in an annular series around the center thereof.

In said drawings, *a* indicates the stair-carpet button, and *b* the central perforation thereof. On the face of the said button, disposed around the said central perforation, are an annular series *c d* of star-shape ornamentations. Between and concentric with the said series of ornaments are ring-like ornaments *e*. The 25 30 groundwork on the surface of the button provides or displays radiating lines or markings, as at *g*.

What I claim as new is—
The design for a stair-carpet button herein 35 shown and described.

In testimony that I claim the foregoing I have hereunto set my hand this 24th day of September, 1896.

DAVID WALKER.
